UNITED STATES PATENT OFFICE.

SAMUEL EDWARD BURCH, OF WELLWOOD, MANITOBA, CANADA.

BALANCED LUBRICATOR.

1,243,252.

Specification of Letters Patent. Patented Oct. 16, 1917.

Application filed December 20, 1916. Serial No. 138,007.

To all whom it may concern:

Be it known that I, SAMUEL EDWARD BURCH, a citizen of the Dominion of Canada, residing at the village of Wellwood, in the 5 Province of Manitoba, in the Dominion of Canada, have invented certain new and useful Improvements in Balanced Lubricators, of which the following is a specification.

My invention relates particularly to apparatus used in connection with steam plants 10 to lubricate the cylinder of the engine, and the object of the invention is to provide a device for the purpose stated in which as it were, the boiler pressure is balanced against 15 itself and the power required to inject the oil into the steam pipe is therefore only that required to overcome the balance between two equal forces. A further object of the invention is to make the apparatus automatic 20 in all its operations so that no attention will be required so long as the supply of oil lasts.

The means by which these and certain other objects of the invention which will 25 develop as the description proceeds, are attained will be found fully set out in the following specification, then more particularly pointed out in the appended claims, reference also being had to the drawings forming 30 part hereof, in which—

Figure 1 is a plan view of a preferred form of the apparatus employing a pair of cylinders.

Fig. 2 is a side elevation of the apparatus 35 as in Fig. 1, a boiler being introduced to show its connection therewith.

Fig. 3 is a sectional view taken on the line 3 in Fig. 1.

Figs. 4 and 5 are face and edge views 40 respectively of the oscillating member through which motion is imparted to the apparatus.

Figs. 6 and 7 are end and bottom views respectively of the valve shifting member.

Fig. 8 shows one of the adjustable dogs 45 which are secured to the valve shifting member.

Figs. 9 and 10 are end and plan views respectively of the frame in which the valve shifting member is slidably supported.

Fig. 11 is a sectional view through the 50 wheel and supporting member relating to one cylinder.

Fig. 12 shows a modification of the apparatus, in which only one cylinder is used.

Fig. 13 is the pawl by which this form of 55 the apparatus is actuated.

Fig. 14 shows the means used to disengage the pawl and ratchet when the supply of oil has become exhausted.

Similar characters of reference indicate 60 similar parts throughout the different views. In these and with special reference to the first ten figures, 1 and 2 are twin cylinders spaced apart at the distance defined by the frame 3 which is secured to each by the 65 rivets 4 or any other suitable means. Pistons 5 and 6 are disposed in the respective cylinders, their rods 7 and 8 passing out through glands 9 adapted to receive some form of packing to render them oil tight. 70 Circular members 10 are supported from the heads of the cylinders at a height approximating the depth thereof, by posts 11, the members 10 being adapted to support on their upper sides the gear wheels 12 and 13, each 75 of the members 10 being provided with a central opening 14 (Fig. 11) to receive revolvably therein the sleeve 15 on the wheel supported thereon. The axial openings 16 through the wheels 12 and 13 are screw-threaded as at 17 and the upper ends of the piston rods 7 and 8 are threaded as at 18 to engage the threads in the wheels, thus the wheels 12 and 13 become revoluble nuts 80 adapted to raise or lower their respective pistons according to the direction in which 85 they are turned on the piston rods.

A shaft 19 crosses the faces of the gear wheels 12 and 13 and is carried in bearings 90 supported from the under sides of the 90 members 10. Opposed worm gears 21 and 22 are carried on the shaft 19 in engagement with the teeth on the gears 12 and 13, so that if the shaft 19 is turned the gears 12 and 13 are revolved in opposite directions.

Approximately midway between the worm gears 21 and 22 a ratchet wheel 23 is secured on the shaft 19 and a vertical member 24 is pivoted on the shaft adjacent the wheel, the vertical member having at its upper end a 95 double ended pawl 25 pivoted thereto in a manner allowing it to be rocked to bring either of its ends 26 or 27 into engagement with the teeth on the ratchet wheel.

The pawl is preferably shaped as shown, 105 that is to say, having a considerable portion above its pivotal point 28 and ending in a diamond shaped point 29. A bracket mem-

ber 30 projects rearwardly from the point of the pawl 25 and a second bracket 31 projects similarly from the member 24 below the pivotal point 28 of the pawl 25, a spring 32 stretching between the brackets under tension and serving to maintain the selected end of the pawl in contact with the teeth on the ratchet wheel 23. A second pawl 33, having the two engaging ends 34 and 35, is pivoted 10 to the lower end of the member 24 at the point 36 and a connecting rod 37 extends between the pawls and is pivoted to both at the points 38 and 39 to synchronize their movements.

15 A longitudinal slot 40 is provided in the member 24 and a horizontal member 41 is pivotally connected to the said member 24 by a bolt 42 which passes through the slot 40. Thus the point of connection between 20 the members 24 and 41 may be changed by raising or lowering the bolt in the slot, and as the horizontal member 41 is connected with some moving part of the engine to which the apparatus pertains, calculated to 25 give to the said member a reciprocating motion in turn causing oscillation of the member 24, the adjustment mentioned becomes useful to control the degree of the said oscillation.

30 The frame 3 is shaped to provide a horizontal channel 43 to receive a member 44, the vertical sides 45 and 46 of the channel ending in the inverted tongues 47 at the top adapted to enter the grooves 48 in the sides 35 of the member 44 to form a sliding engagement therewith. Longitudinal slots 49 and 50 are formed in the member 44, and dogs 51 and 52, preferably shaped as shown in Fig. 8, are adjustably secured on the upper 40 side of the member 44 by bolts which pass through the said dogs and slots and which are supplied with tail nuts 53 by which they may be readily released when an adjustment of the distance between the dogs is indicated.

45 This change of adjustment would be necessary at such times as a change in amount of the oscillation of the member 24 were made, as the dogs control a valve movement hereinafter described.

50 From the description to this point it will be understood that as the vertical member 24 is constantly oscillated by the member 41 the wheel 23 will be intermittently revolved by the pawl 25, the direction of this movement depending upon which of the ends 26 or 27 is in contact with it, and that as the wheel is revolved one of the pistons in the cylinders will be raised while the other is lowered. To reverse the movement at the 55 proper time uprights 54 are secured to the cylinders 1 and 2, these providing forks 55 at their upper ends to receive the levers 56 and 57 pivotally therein, these being maintained normally horizontal by the 60 springs 58, with their rear ends 59 directly

over the piston rods 7 and 8 respectively and their front ends 60 positioned to engage the faces 61 and 62 of the point 29 of the pawl 25 when the levers are dipped.

The ends 60 of the levers 56 and 57 are preferably turned as shown, to stand parallel with the faces of the point 29 on the pawl.

In Figs. 2 and 3 the piston 6 is at the bottom of its stroke and piston 5 at the top, the rod 7 of the latter having reached and elevated the rear end 59 of the lever 56, thus depressing the point 60 against the face 61 of the pawl 25 and operating to throw the said pawl over the dead center, the spring 32 then bringing the point 27 of the pawl into contact with the teeth on the wheel 23. The motion of the wheel 23 has thus been reversed and the piston rod 7 will now descend and piston rod 8 will ascend until it has performed a similar function with the lever 57.

As the pawls 25 and 33 are connected by means of the rod 37 the latter pawl has partaken of the movement of the former and the end 33 thereof been positioned to engage the dog 51 on the member 44 and slide 90 the same.

The piping system by means of which the operations described are made of useful effect comprises the pipes 63 and 64 which open into the cylinders 1 and 2 at the top 95 thereof, these two pipes joining at the T 65 and thereafter becoming the pipe 66 opening into the steam pipe 67 leading from the boiler 68 above the water level, to the steam chest of the engine, not shown. The pipes 63 and 64 have in their lengths the check valves 69 and 70, each closed against pressure from the boiler. The pipes 71 and 72 run from a suitable supply of oil such as a tank or barrel and join the pipes 63 and 64 inside their check valves as shown in Fig. 1, the pipes 71 and 72 being themselves provided with the check valves 73 and 74 closed against pressure from the pipes 63 and 64.

A pipe 75 running from the boiler 68 below the water line branches into the pipes 76 and 77 connecting respectively with the cylinders 1 and 2 below their pistons 5 and 6. The pipes 76 and 77 have respectively in their lengths the quarter turn three way valves 78 and 79, the levers 80 and 81 of which are pivoted to the links 82 and 83, these in turn being pivotally connected to the slideable member 44. 84 and 85 indicate waste pipes connected with the valves 78 and 110 79, these valves being opposed so that a movement that closes the waste connection in the one opens that in the other.

In operation, in view of the positions of the parts in the drawings, as previously 125 mentioned the piston 7 will now descend and that 8 will ascend. At the first oscillation of the member 24 toward this movement the point 34 of the pawl 33 would engage the dog 51 on the member 44, the reverse oscil-

lation serving to slide the member 44 the length of the swing of the member 24, after which the further oscillations of the member 24 would have no effect at this point until a reversal of the pawls caused the point 5 35 to engage the dog 52 when the member 44 would be returned to its original position. By the first movement of the member 44 as just described, the levers 82 and 83 of the 10 valves 78 and 79 would be moved a quarter turn through their link connection with that member, thus closing the connection of the pipe 76 with the boiler by way of the pipe 75, and opening it to waste through the pipe 84 to drain the cylinder 1. The same movement closed the waste pipe 85 and opened 15 the boiler connection to the cylinder 2 through the pipe 77. Thus the boiler pressure (water) is exerted under the rising piston 6, and the oil above the piston is fed 20 through the pipes 64 and 66 into the steam pipe 67 from which it passes with the steam into the engine. The cylinder 1 is free from boiler pressure as mentioned and as the piston 5 therein descends the oil feeds in 25 through the pipe 71 past the check valve 73 into the pipe 63 and thence into the cylinder, until the reverse operation takes place. Thus it will be seen that the operations alternate in the cylinders so long as the apparatus 30 is in operation and the supply of oil lasts.

Should the oil feed too rapidly the pivotal connection between the reciprocating member 41 and the oscillating member 24 is 35 raised to reduce the length of the oscillation, thus reducing the movement of the wheel 23 and the amount of oil fed to the engine. When this adjustment is made it calls for a 40 readjustment of the position of the dogs 51 and 52 on the member 44, these being necessarily brought closer together in order that the slide of the member 44 may be the same length as before, this being necessary to 45 bring about a complete quarter turn of the valves 78 and 79.

Thus it will be seen that the rising piston is supported by boiler pressure from below the water line in the boiler as it feeds the 50 oil against the boiler pressure from above the water line, the pressure being thus balanced and the power required to overcome the balance merely nominal.

In Fig. 12 a modification of the apparatus 55 is shown, in that it consists of but a single cylinder 1, and while the oil is automatically fed in by the pawl and ratchet 25 and 23, the other operations are performed by hand. In this form, when the piston rod 7 reaches its 60 upward limit it operates the bell-crank lever 86 to depress the rearwardly extending arm 87 connected with the pawl 25, thus removing the pawl from contact with the teeth on the wheel 23 and stopping all movement of the 65 apparatus aside from the oscillation of the

member 24. In this case the worm gear 21 is slidably mounted on a squared portion 88 of the shaft 19 and a spiral spring 89 maintains the gear normally in working position. When the apparatus stops the worm gear 21 is slid by hand out of contact with the gear 12 and the piston run down by means of the handle 90 which is secured to the gear 12. The boiler pressure below is cut off and water drained from the cylinder 70 by means of the valve 91 while the piston is being lowered, and the cylinder is filled with oil through the screw-topped funnel 92. In other respects the apparatus and its functions 75 are the same as previously described. 80

Having thus fully described my said invention, what I claim is—

1. An apparatus of the kind described comprising a boiler having a steam pipe, a cylinder having connection with an inlet pipe for lubricant and an outlet pipe for the same connected with the steam pipe, back pressure valves in the inlet and outlet pipes, a piston in the cylinder, suitable means to operate the piston to expel the lubricant, a connection between the boiler below the water line and the cylinder behind the piston and a cock to control the flow of water through the said connection. 85

2. An apparatus of the kind described comprising a boiler having a steam pipe, a pair of cylinders having at one end inlet pipes for a lubricant and outlet pipes for the same connected with the steam pipe, back pressure valves in the inlet and outlet pipes, pistons in the cylinders, means to operate the pistons in opposite directions to receive and expel the lubricant, water pipes connecting the boiler below the water line with the cylinders behind the pistons, cocks 100 in the water pipes, and means to reverse the movements of the pistons and simultaneously operate the cocks in the water pipes to allow one cylinder to fill with water and to 105 drain the other. 110

3. An apparatus of the kind described comprising a boiler having a steam pipe, a pair of cylinders vertically positioned and having at their upper ends inlet pipes for a lubricant and outlet pipes for the same connected with the steam pipe, back pressure valves in the inlet and outlet pipes, water pipes at the lower ends of the cylinders connecting with the boiler below the water line, cocks in the water pipes, pistons in the cylinders, pawl and ratchet means to operate the pistons in opposite directions, and means operatively connected to automatically reverse the pistons at the limit of their movement and operate the cocks to allow water 115 to enter the cylinder behind the ascending piston and to drain it from behind the descending one. 120

4. An apparatus of the kind described comprising a boiler having a steam pipe, a 130

pair of cylinders, inlet pipes for a lubricant and outlet pipes for the same connecting the cylinders and the steam pipe, pistons in the cylinders oppositely operated to receive and 5 expel the lubricant, water pipes connecting the boiler below the water line with the cylinders behind the pistons, and means in

the water pipes automatically operated to open boiler connection with the expelling cylinder and to close it with the receiving 10 cylinder, and drain the latter.

In testimony whereof, I affix my signature.

SAMUEL EDWARD BURCH.
